PINKING MACHINE

William P. Niukkanen, Portland, Oreg.

Application March 9, 1934, Serial No. 714,860

1 Claim. (Cl. 164—64)

This invention relates to pinking machines, and has for its object the production of a simple and efficient means which may be readily attached to a sewing machine and which may be operated thereby for facilitating the cutting or forming of a pinked edge upon cloth or other material.

Another object of this invention is the production of a simple and efficient means for adjusting the pressure wheel relative to the cutter or pinking wheel, so as to provide an efficient cutting medium for the cloth or other material to be pinked.

A further object of this invention is the production of a simple and efficient supporting means for the pinking wheel, the pressure wheel, and other associated parts, as well as the means for anchoring the parts in position for actuation by the needle operating bar or chuck.

With these and other objects in view, this invention consists in certain novel constructions, combinations and arrangements of parts as will be hereinafter more fully described and claimed.

In the drawing:—

Figure 1 is a side elevation of a portion of a sewing machine equipped with the pinking attachment;

Figure 2 is an end elevation of a portion of the sewing machine showing the pinking attachment secured thereto;

Figure 3 is a section taken on line 3—3 of Figure 2;

Figure 4 is a section taken on line 4—4 of Figure 1;

Figure 5 is a vertical section taken on line 5—5 of Figure 2, the cloth plate being removed;

Figure 6 is a section taken on line 6—6 of Figure 5; and

Figure 7 is a section taken on line 7—7 of Figure 5.

By referring to the drawing, it will be seen that 1 designates the sewing machine which is provided with the usual needle operating bar or chuck 2. The cloth plate 3 of the usual type, is located below the needle operating bar and chuck, as shown in Figure 1, and may be of the usual and commercial type. The present pinking attachment comprises a supporting block 4 which rests upon the cloth plate 3, as shown in Figures 1 and 2 and this block 4 is anchored in position by means of a binding or set screw 5 which passes through the slotted end 6 of the anchoring bar 7 and secures this anchoring bar 7 in a set position upon the cloth plate 3. The supporting block 4 is provided with an enlarged cut-out portion 8

upon one side thereof to provide a lower bearing support 9 and an upper bearing support 10. A suitable bushing or sleeve 11 is carried by the lower bearing support 9, as shown in Figure 5 and a pinking wheel supporting shaft 12 extends through the bushing or sleeve 11 and through this lower bearing support 9. Upon the outer end of the pinking wheel supporting shaft 12 is mounted the cutter disc or pinking wheel 13, the surface of which is preferably zig-zag, as that clearly indicated in Figures 1 and 5 which causes a toothed effect in the trimming edge of the fabric or other material to be pinked. The opposite end of the shaft 12 supports a ratchet wheel 14 and a lever 15 is loosely mounted upon this shaft 12 and is held thereon by means of a suitable locking nut 16. A spring pressed pawl 17 is carried by this lever 15 and engages the ratchet wheel 14 so as to drive or rotate the shaft 12 in one direction as this lever 15 is oscillated. One end of the lever 15 is bifurcated, as indicated at 18, for facilitating the connection thereof with the needle operating bar or chuck 2 by means of a suitable locking screw 19. It will therefore be seen that as the needle operating bar or chuck 2 reciprocates the lever 15 will be oscillated and through the actuation of the pawl and the ratchet described, the shaft 12 will be rotated and the pinking wheel or disc 13 which is keyed or locked upon the shaft 12, will also be rotated.

The upper bearing support 10 carries a shaft 20 which is locked against longitudinal movement by means of the locking screw 21 in the conventional manner, fitting in the groove 22. A bearing block 23 is fitted within a socket 24 formed in the underface of the upper bearing support 10 and this bearing block 23 is preferably square or rectangular in cross-section and constitutes a support through which the greater length of the shaft 20 passes. A pressure wheel 25 of substantially the width of the pinking disc or wheel 13 is carried by the outer end of the shaft 20 and the periphery thereof normally contacts with the zig-zag edge of the pinking wheel or disc 13 as shown clearly in the drawing. In order that the pressure wheel 25 may be adjusted so as to firmly contact with the cutting edge of the pinking wheel or disc 13, a binding screw 26 is provided which is carried by the upper bearing support 10 and contacts with the bearing block 23, as shown in Figures 5 and 7 whereby the pressure wheel 25 may be forced into adjusted relation with the edge of the pinking disc or wheel 13. From the foregoing description it will be seen that a very simple and efficient means has

been provided for facilitating the adjustment of the pressure wheel 25 relative to the pinking disc 13 and thereby facilitate the cutting or pinking of the edge of the material passing between the disc 13 and the wheel 25. A supporting table for the material to be pinked is indicated by the numeral 27 and this table may be of any suitable size or character and is provided with a suitable aperture 28 through which the periphery of the pinking disc or wheel 13 extends, as shown in Figure 4. An abutment bracket 29 is adjustably supported upon the block 4 and may be locked in position by means of a suitable locking screw 30, the abutment bracket 29 having a right angularly extending lip 31, which lip is adapted to extend in back of the contact points of the disc 13 and wheel 25, as shown in Figure 4. This bracket 29 will permit of a proper adjustment so as to constitute an abutment against which the edge of the cloth or

other material may rest while guiding the pinking material through the pinking apparatus.

It should be understood that certain detail changes in the mechanical construction may be employed without departing from the spirit of the invention, so long as these changes fall within the scope of the appended claim.

Having described the invention, what is claimed as new is:—

A pinking machine of the class described comprising a support, a table carried by said support, a pinking wheel, a shaft supporting said pinking wheel, a lever carried by said shaft, ratchet means for rotating said shaft as said lever is oscillated, means for anchoring said support adjacent the needle operating bar of a sewing machine, an abutment bracket adjustably mounted upon said support and resting upon said table, and a pressure wheel carried by said support in contact with said pinking disc.

WILLIAM P. NIUKKANEN.
